UNITED STATES PATENT OFFICE.

COULTON WAUGH, OF NEW YORK, N. Y.

DESIGN FOR A TEXTILE FABRIC FOR DECORATIVE PURPOSES.

56,213.

Specification for Design.

Patented Aug. 24, 1920.

Application filed April 3, 1920. Serial No. 371,172. Term of patent 3½ years.

To all whom it may concern:

Be it known that I, COULTON WAUGH, a citizen of the United States, residing at 428 Lafayette street, city of New York, in the county and State of New York, have invented a new, original, and ornamental Design for a Textile Fabric for Decorative Purposes, of which the following is a specifica-

tion, reference being had to the accompanying drawing, forming part thereof.

The figure is a plan view of a piece of textile fabric showing my new design.

I claim:

The ornamental design for a textile fabric for decorative purposes, as shown.
